[57] CLAIM

The ornamental design for a cordless electric hair curling iron or similar article, as shown and described.

DESCRIPTION

FIG. 1 is an elevational view of one side of cordless electric hair curling iron or similar article showing our new design. The side opposite to the one shown in FIG. 1 is a mirror image of FIG. 1.

FIG. 2 is a top view thereof.

FIG. 3 is a front end view thereof.

FIG. 4 is a rear end view thereof.

FIG. 5 is a bottom plan view thereof.

FIG. 1

FIG. 2

FIG. 3

FIG. 4

FIG. 5
